UNITED STATES PATENT OFFICE.

LUCIEN A. DEXTER, OF GRAND RAPIDS, MICHIGAN.

LATCH.

Application filed March 22, 1927. Serial No. 177,252.

This invention relates to a door latch of the type used for releasably holding doors in closed position, wherein the latch is located in a recess or mortise in the edge of the door and is operated by the usual door knobs, one connected at each end of a bar, usually square in cross section, which passes through the door and through the latch.

The present invention relates to certain improvements in latches, the housings of which are substantially of cylindrical form so that installation on the door is easily accomplished by merely boring a hole of the required diameter in the edge of the door for the reception of the latch, with another hole bored transversely through the door and across the hole bored to receive the latch for the passage of the operating bar of the latch.

It is an object and purpose of the present invention to construct economically a practical and serviceable latch which is easily installed and which is sure and effective in its operations. Particularly, the latch as constructed is always free in its workings and does not stick or bind after being in service for a time. Moreover the construction is one which, in its assembly, is especially simple. For an understanding of the invention whereby these ends, as well as others not stated, are attained, reference may be had to the following description taken in connection with the accompanying drawing, in which,

Fig. 1 is a longitudinal vertical section through the latch with the latch bolt in its normal projected position.

Fig. 2 is a like view showing the bolt retracted.

Fig. 3 is a fragmentary enlarged vertical section taken transversely through a door with the latch of my invention installed therein, the section being substantially in the plane of the operating member for the latch, and

Fig. 4 illustrates in perspective certain elements of the latch bolt operating mechanism disassembled and separated from each other.

Like reference characters refer to like parts in the different figures of the drawing.

The latch housing comprises two halves or parts 1 of semi-cylindrical form which, when placed together, are connected and held together by a rear or inner cap 2 and a front sleeve 3 to which a plate 4 is permanently secured, the same lying against the edge of the door when the latch is assembled therewith. Within the outer end of the cylindrical hous-

ing thus made a rod 5 is located centrally and lengthwise of the housing, to which a head 6 is attached, the same normally projecting through an opening in the plate 4. This rod 5 and head 6 make a latch bolt and the head is provided with the ordinarily beveled strike side (not shown) common to latch bolts of this character. At its inner end the rod 5 is equipped with a somewhat enlarged head 7 between which and the main body of the rod 5 is a flattened section 8 adapted to detachably connect with a disc 9 slotted at one side, at 10, the slot at its inner end joining with a substantially circular opening 11, as shown in Fig. 4. The flattened portion 8 passes readily through the slot 10 and is received in the opening 11. A coiled spring 12 of light strength is located around rod 5 between the head 6 and the disc 9 as shown.

The disc 9 is permanently secured at the outer end of a U-shaped member of sheet metal which has two spaced apart legs 13 connected at their inner ends by a cross portion 14. The outer ends of the legs 13 pass through suitable openings in the disc 9 and are riveted to make a secure and permanent connection therewith. At the inner side of each of the legs 13 two notches or recesses 15 and 16, of the form shown, are made, the notches 15 being cut deeper than notches 16 and being located back thereof. Back of the notches 15 and between the inner ends of legs 13, is a rectangular recess 17. A relatively strong coiled spring 18 is disposed between the bottom of the cap 2 and the cross portion 14 of the U-shaped member, the tendency of which is to force said U-shaped member and the latching bolt connected therewith in an outward direction.

At opposite sides of the U-shaped member described, two members pressed from sheet metal are located, each comprising a flange 19 from the center of which a cap 20 is pressed outwardly, the outer portion 21 of which is reduced in diameter. Each of the caps has a square opening 22 in its end. To one of the flanges 19 two shouldered pins 23 are secured in spaced apart relation, while the flange 19 of the opposite member has suitable openings to receive the reduced free ends of the pins 23. The parts 1 of the cylindrical housing have openings made therethrough in which the reduced end portions 21 of the caps are received as shown in Fig. 3.

This locates the legs 13 of the U-shaped member between the flanges 19 with the pins 23 extending across and in front of the rear edge portions of the recesses 15 in said legs 13, as shown in Fig. 1.

When the latch is installed on a door, indicated at 24 in Fig. 3, the housing with the latch bolt and operating structure described, is inserted in a cylindrical opening bored in 10 the edge of a door and a square operating bar 25 is passed through the door through an opening made for that purpose, the same passing through the square openings 22 described as made in the ends of the caps 20. 15 The usual knobs 26, a fragment only of which are shown in Fig. 3, are attached to the ends of the bar 25 with the usual rosettes 27 between the knobs and the door.

It is evident that on turning a knob at 20 either side of the door in either direction, one of the pins 23 will engage against the rear shoulder of the recess 15 in which it is located and will retract the bolt, compressing the spring 18 and moving the other pin 25 until it is stopped by seating in the recess 16 in front of the recess 15 engaged by the first pin. This operation is illustrated in Fig. 2 and the bolt is retracted so as to withdraw the head 6 and bring its outer end substantially flush with the outer surface of the 30 plate 4. Such operation will occur irrespective of which way the bar 25 is turned. When the door is closed the beveled side of the head 6 riding against the strike plate on 35 the door jamb causes the bolt to move inwardly with a compression of the spring 12, and as soon as the latch reaches proper position the spring 12 projects the head 6 outward to connect said head with the strike 40 plate on the door casing or jamb.

This construction is very economical to produce. The U-shaped member, the disc 9 and the two cap members with their flanges 19, are of sheet metal which can be worked 45 very rapidly by means of suitable dies so as to make a large quantity production at low cost. The construction is perfect in its operation and does not get out of order, does not bind or stick in the housing and remains 50 operable for an indefinite period. The construction has proved very satisfactory and is being manufactured and sold in large quantities. The invention is defined in the appended claims and is to be considered comprehensive of all forms of structure coming 55 within their scope.

I claim:

1. A door latch comprising a substantially cylindrical barrel, a latch bolt mounted 60 therein and having a head at one end adapted to project beyond an end of the barrel, said latch bolt including a U-shaped member of flat metal each of the legs of which at its inner side is formed with two spaced apart notches, an operating bar extending

through the cylinder and between the legs of said U-shaped member, an operating device comprising two members of sheet metal each having an annular flange and a cap pressed centrally outward therefrom disposed one at each side of the U-shaped member, and spaced apart pins connecting the flanges of said members and normally located in the opposite innermost notches in the legs of said U-shaped members, substantially as for the purposes described. 70

2. A door latch comprising a housing, a latch bolt mounted for reciprocation in the housing including a U-shaped member of flat metal having spaced apart legs, an operating bar extending through the housing and between the legs of said U-shaped member, a member of sheet metal comprising an annular flange and a cap extending outwardly centrally therefrom located one at each side of the U-shaped member through which said bar passes, and means disposed between said flanges and means on the legs of said U-shaped members adapted to be engaged by said first means for retracting the bolt on 80 turning said bar in either direction.

3. A door latch comprising, a housing, a latch bolt mounted for reciprocation in said housing, including a U-shaped member of flat metal, spring means acting on the bolt to normally move it to outer position, a bar passing through the housing and between the legs of said U-shaped member, means connected with the bar and means on the legs of said U-shaped member with which said first mentioned means engages for retracting the bolt against said spring on turning said bar. 90

4. A latch comprising a housing, a latch bolt mounted therein for reciprocatory movements including a U-shaped member of flat metal, spring means acting against the inner end of said U-shaped member for normally projecting the bolt outward, an operating bar passing transversely through said housing and between the legs of said U-shaped member, a member located one at each side of the U-shaped member within said housing through which said bar passes, pins connecting said last named members, said legs of the U-shaped member being formed with opposed notches at the inner side for the reception of said pins and said pins being located in a plane outward of a vertical plane passing through the longitudinal axis of said bar whereby on turning the bar in either direction the latch bolt is retracted. 105

5. A latch comprising a cylindrical housing having an opening at one end, a latch bolt mounted for reciprocation in said housing having a head extending through said housing, said bolt including a member of U-shape having spaced apart legs each formed at the inner side with two notches, a bar pass- 115 120 125

- ing transversely through said housing between the legs of said U-shaped member back of said notches, an operating member of sheet metal comprising an annular flange and
- 5 an outwardly pressed cap at the center of said flange located one at each side of said U-shaped member, said bar passing through both of said operating members, said housing at opposite sides having openings at
- 10 which the outer ends of the caps are rotatably received, and pins connecting said flanges and normally located in the innermost notches one in each leg of said U-shaped member whereby on turning the operating
- 15 bar in either direction the latch bolt is retracted, one of said pins remaining in the notch in which it is located and the other extending in the foremost notch in the same leg of the U-shaped member at the extreme
- 20 inner position of the latch bolt.
6. In a latch, a housing, a latch bolt mounted for reciprocation in said housing comprising a U-shaped member having spaced apart legs, a disc secured at the free ends of said legs, said disc having a radial slot therein enlarged at its inner end at the center of said disc, a headed rod having flattened portions at each side adjacent said head connected with said disc, the flattened portions being
- 25 received in said slot and a latching head at the outer end of the rod, an operating bar square in cross section extending transversely through said housing between the legs of said U-shaped member, a spring acting on said
- 30 bolt normally projecting the same outward, and means on the operating bar engaging in means formed at the inner sides of said legs of said U-shaped members for retracting said bolt on rotating the bar on its longitudinal axis in either direction.
7. A door latch comprising a housing, a
- latch bolt reciprocally mounted in the housing and having a longitudinally elongated aperture, said aperture having two notches in each of its longer sides and a rotatable 45 actuating member having two pins arranged to enter said notches and by rotation of the actuating member in either direction to retract said latch bolt.
8. A door latch comprising a housing, a latch bolt reciprocally mounted in the housing and having a longitudinally elongated aperture, said aperture having two notches in each of its elongated sides, one notch of each bar being deeper than the other and a rotatable 55 actuating member having two pins arranged to enter said aperture and said notches therein whereby upon rotation of the actuating member in either direction one pin will first enter the deeper serration following which 60 in the rotation the other pin will enter the shallower serration and stop rotation of the actuating member.
9. A door latch comprising a housing, a latch bolt reciprocally mounted in the housing and having a longitudinally elongated aperture, each of the elongated sides of said aperture having notches, an actuating rotatable shaft extending through the housing and through said aperture, two rotatable 65 members located within the housing one on each respective side of said latch bolt, said shaft extending through said rotatable members and fixed thereto, two pins extending through the said aperture in the latch bolt 70 and connected at each end to the respective rotatable members, said pins being arranged to enter said notches upon rotation of the rotatable members in either direction to reciprocate the latch bolt.
- 80

In testimony whereof I affix my signature.
